CLAIM

The ornamental design for a device for storing papers or the like, as shown and described.

DESCRIPTION

FIG. 1 is a perspective view of a device for storing papers or the like.

FIG. 2 is a front view of the device of FIG. 1.

FIG. 3 is a left side view of the device of FIG. 1.

FIG. 4 is a right side view of the device of FIG. 1; and,

FIG. 5 is a top view of the device of FIG. 1.

The broken lines in FIGS. 1-5 are for environmental purposes only and form no part of the claimed design.
